Attorney

UNITED STATES PATENT OFFICE.

FREDERICK ULRICH, OF PERU, INDIANA.

WAGON-AXLE TRUSS.

SPECIFICATION forming part of Letters Patent No. 312,676, dated February 24, 1885.

Application filed December 27, 1884. (No model.)

To all whom it may concern:

Be it known that I, FREDERICK ULRICH, a citizen of the United States, residing at the city of Peru, in the county of Miami and State of Indiana, have invented certain new and useful Improvements in a Wagon-Axle Truss; and I do hereby declare that the following is a full, clear, and exact description of the same, reference being had to the annexed drawings, making a part of this specification, and to the letters and figures of reference marked thereon.

Figure 1 of the drawings is a front elevation of a bolster and axle embodying my invention; Fig. 2, an under side plan view, on an enlarged scale, of the axle, showing the manner of attaching the truss-rods thereto; and Fig. 3, a similar view of a modification of my invention.

The present invention has relation to the manner of connecting the ends of truss-rods to the axles of vehicles, and is designed as an improvement on my former patent, No. 278,755, dated June 5, 1883; and the invention consists in bringing the ends or extremities of the truss-rods around lugs depending from the under side of the axle, the ends of the rods being bent in opposite directions around each lug and secured by clamping-plates, substantially as shown in the drawings, and hereinafter described and claimed.

In the accompanying drawings, A represents the axle, and B the bolster, said axle being provided with the usual thimble-skeins, C.

Upon the under side of the axle A, and 35 near each end thereof, are depending lugs *b c*,

the outer lugs, *b*, forming guides for the ends of the truss-rods D, which are bent around the lugs *c*, the extremities of the rods located between the lugs *c* abutting or bearing against each other, as shown, and are held in place 40 between the lugs by the usual clamping-plates, *d*, and clips *c*.

In Fig. 3 I have shown a modification of my invention, the extremities of the truss-rods being bent in opposite directions to those 45 shown in Fig. 2.

In the present instance I have preferred the use of two independent rods extending the entire length of the axle; but a single rod may be used, halved or split at its extremities and 50 bent around the lugs in the manner above described; and, if preferred, the outer lugs, *b*, may be dispensed with, and the extremities of the truss-rods simply bent around the lugs *c*.

Having now fully described my invention, 55 what I claim as new, and desire to secure by Letters Patent, is—

A truss for axles, consisting of a rod or rods passing between lugs depending from the under side of the axle and afterward bent around 60 the same, substantially as and for the purpose set forth.

In testimony that I claim the above I have hereunto subscribed my name in the presence of two witnesses.

FREDERICK ULRICH.
